UNITED STATES PATENT OFFICE

HAROLD H. HENRICKS, OF CHICAGO, ILLINOIS, ASSIGNOR TO THE YOUNGSTOWN STEEL
DOOR COMPANY, OF CLEVELAND, OHIO, A CORPORATION OF OHIO

CAR-DOOR MOUNTING

Application filed September 12, 1925. Serial No. 55,932.

This invention relates to car door mountings.

An object of the invention is to provide a track arrangement for car doors for supporting and guiding the same in their sliding movements, which will be simple in construction, efficient in operation, and inexpensive to build.

A further object of my invention is to provide a fabricated hanger construction which may be made up from cold pressed metal, to reduce the cost of manufacture, the component parts of said fabricated hanger arrangement being of such character that the same are capable of being assembled in a simple and effective manner.

Another object of the invention is to provide in a hanger construction, a roller housing and wheel or roller mounting whereby the inner face of the housing is free of obstructions, and a suitable clearance is provided for the roller to minimize friction.

Other and further objects of the invention will more clearly and fully appear from the description and claims hereinafter following.

In the drawing forming a part of this specification, Figure 1 represents a fragment of the car and door structure, showing my invention applied thereto; Figure 2 is a fragmentary, enlarged, vertical, transverse, sectional view of the invention as shown in Figure 1; Figure 3 is a fragmentary view of a portion of the car and door structure showing a slightly different embodiment of the invention; Figure 4 is a fragmentary, enlarged, vertical transverse sectional view of the invention as illustrated in Figure 3; Figure 5 is a front elevational detail view of a hanger of the character contemplated by my invention; Figure 6 is a part, transverse sectional, and part side elevational view, of the hanger illustrated in Figure 5; Figure 7 is a transverse vertical section of the upper portion of the hanger showing the roller housing, with the roller mounted in said housing; and Figure 8 is an enlarged, detail, transverse sectional view of the roller used in connection with my invention.

Referring first to Figures 1 and 2 of the drawings, 10 represents the cross lintel of the

door frame, 11 one of the door posts, and 12 a door, which in this instance is preferably made up entirely of sheet metal. Disposed on the inner side of the lintel timber 10 is one flange 13 of a lintel supporting angle bar 14, 55 the other flange 15 of said bar being disposed above the top of the lintel member, and adapted to rest upon the flange 16 of the angle bar 17, the remaining flange 18 of the angle bar 17 being disposed downwardly and fitted into 60 a rabbet 19 formed in the lintel 10, the flanges 15 and 16 of the angle bars 14 and 17 being secured together by any suitable means in the completed car structure, as will be understood. Disposed against the flange 18 of the 65 angle 17 is the upright flange 20 of an angle bar 21, the flanges 20 and 18 of the angle bars 17 and 21 being secured together by rivets 22 as shown. The remaining flange 23 of the angle member 21 has its inner edge 24 resting 70 upon the top surface of the header 25 of the door frame, the flange 23 extending outwardly of the door frame and providing the track proper. Secured to the under surface of the flange 23 is a smaller angle bar 26, the horizontal flange 27 of which projects inwardly 75 into a cut-out portion 28 in the upper portion of the header 25, the horizontal flange 27 being secured to the under surface of the flange 23 of the track proper by suitable rivets indicated at 29. The flange 30 of the angle member 26 extends vertically downwardly a suitable distance and is spaced outwardly from the outer face of the header 25 to provide a relatively narrow guide-way for the accommodation of the upper edge of the door 12. 80

By the above described arrangement it will be appreciated that the track member is supported from inside of the lintel timber so as to provide a strong and efficient construction. 90

Secured to the upper edge of the door are the hangers 31, preferably two in number, both of which are alike, and only one of the same will be described in detail. Each hanger 31 comprises a lower portion having perforated ears 32, by which, and the bottom flange, the hanger is secured to the door, suitable rivets being employed for this purpose as indicated at 33. The body portion 34 of each hanger 95 is inclined upwardly and outwardly, and on 100

the inner side of said hanger, the same is provided with a horizontally disposed off-set 35, spaced from the top edge of the door, said off-set normally clearing the lower edge of the flange 30 of the angle bar 26, said off-set portion 35 having a rounded or convex upper surface 35^a. As hereinafter described, the door is supported from rollers on the track 23, which is in a plane above the top edge of the door. By employing the rounded or convex surfaces 35^a, on the brackets, which rounded surfaces are directly below the depending flange 30, tilting or cocking of the door, while being shifted, is definitely limited by regulating the amount of clearance between said rounded surfaces and the lower edge of the flange 30. In practice, this clearance will be so made that no part of the bracket will engage with the track section 23 nor will the upper edge of the door engage with the flange 27. By rounding the offset 35, the friction between the surface 35^a and the depending flange 30 is reduced to a minimum, regardless of the direction in which the door may be tilted or shifted.

25 The body portion 34 is extended outwardly a sufficient distance to clear the outer edge of the track 23, said hanger being turned vertically upwardly at this point, and provided at its extremity with an inwardly turned portion forming a housing 135. The housing 135 is provided with a top wall 36, and spaced inner and outer walls 37 and 38. The inner of said walls is provided with a journal opening 39, and the outer of said walls is provided with a smaller journal opening 40, said journal portions being of a size to accommodate a stepped axle 41, the enlarged portion 42 of which is disposed in the larger opening 39 and extends across said housing into abutment with the inner surface of the outer wall 38 of the housing, the reduced portion extending through the smaller opening and outwardly of the housing, where it is provided with a retaining pin 42, it being noted that the inner end of the axle terminates in a plane common with the plane of the inner surface of the inner wall 39. Mounted upon the axle 41 is a roller 43, said roller preferably being provided in its axial opening with a graphited bronze self-lubricating bushing 44.

50 Referring now to Figures 3 and 4, another embodiment of the invention is disclosed. In this construction it is necessary that the track project outwardly from the car side a considerable distance. In this arrangement a Z-bar 50 is provided which extends along the top of the car side above the door opening, and is properly secured in position. Secured to the flange 51 of the Z member 50 by means of rivets indicated at 52, is an extension plate 53, which projects beyond the door opening, as indicated at 54, and provides the track proper. Secured to the under surface of the plate 53 is a small angle member 54^a, the

flange 55 of said angle member projecting vertically downwardly a suitable distance and co-operating with the door frame to provide a guide for the upper edge of the door 55. Secured to the upper edge of the door are hangers 56, which are identical with the hangers 31 heretofore referred to, each hanger having a roller arrangement adapted to cooperate with the track 54. Each of said hangers is also provided with a rounded or convex off-set 57 adapted to contact with the lower edge of the guide angle 55 for the same purpose as the rounded off-set 35^a previously described. In other words, the convex or rounded off-set 57 will prevent the upper edge of the door proper from engaging any of the track structure and will also prevent any other part of the bracket from coming in contact with any of the track structure.

Referring now to Figures 5 to 8, inclusive, there is shown a hanger of a built-up or fabricated construction, the component parts of which are of such design that they may be pressed from cold metal, and subsequently assembled. Said hanger includes a base portion 100, a body portion 101, and a housing made up of complementary sections 102 and 103. As above stated, the parts of the hanger are preferably pressed separately from cold metal in order to reduce the cost of the same to a minimum, one part of said hanger including the base, body portion, and one section 102 of the housing. The lower extremity of the base portion 100 is flat, and immediately above said portion is provided a pressed, substantially triangular ridge 104, the apex of which is disposed upwardly, and the sides 105 of which slope laterally of said hanger, this construction affording a shedding member to prevent corrosion and the accumulation of foreign matter. The body portion 101 of the hanger is offset to one side, as best shown in Figure 6, and is curved laterally to afford a maximum of strength, the upper portion of said hanger being provided with an inturned, substantially semi-circular flange 106, which provides one side of the housing, the wall 107 of such portion having a journal opening 108. The complementary portion of the hanger housing 103 is also provided with an inturned flange 109 of a size to fit snugly within and overlap the flange 106 of the member 102, the flanges 106 and 109 being secured together by rivets 110. The side wall 111 of the member 103 is depressed or inwardly offset as indicated at 112, and the depressed portion provided with a journal opening 113, it being noted that the depressed portion provides clearance from the inner face of the wall 111 for the roller which is disposed in said housing.

The roller which is used in connection with a hanger of this type, is provided with a hub section 114, which projects outwardly beyond

the corresponding side edge of the tread 115 of said roller, the other hub section 116 of said roller lying in the same plane as the periphery of the roller tread. In the axial 5 opening 117 of said hub is provided a self-lubricating bushing 118, preferably of graphited bronze. The roller of this construction is adapted to be disposed between the side walls 107 and 111 of the housing, and in 10 order to mount the roller in the housing I utilize a stepped axle 119 of the same character as the axle 41 heretofore referred to, said axle being retained in position by means of a suitable pin 120. It will be noted that 15 clearance is afforded the roller in the housing by reason of the depressed portion of the side wall 111 and by the engagement of the projecting hub 114 on the roller with the wall 107, and it will be further noted that the 20 axle 119 terminates flush with the outer side of the depressed portion 112. By insuring clearance of the roller from each side wall of the housing and by employing a self-lubricating bearing for the roller, the friction of 25 the supporting rollers is reduced to a minimum, an important consideration in car door structures. Furthermore, while I have described specifically the roller bracket and housing as preferably made from cold pressings, nevertheless it will be understood that 30 the bracket and housing may be made in other manners while still embodying certain of the features of the invention.

Particular attention is called to the arrangements as illustrated in Figures 2 and 4. As hereinbefore described, my improvements are primarily adapted for doors of sheet metal construction and the supporting rollers and brackets are also particularly designed for doors of this type, as distinguished 40 from wood doors, for instance. In the type of doors illustrated in the drawings, the main portions preferably comprise relatively thin sheets of metal suitably reinforced by corrugations extended outwardly from the main 45 plane of the door, the margins of the door being additionally reinforced by plates or strips providing a multiple-ply edge. As will be understood, this construction will 50 preferably be carried out on all four edges of the door, similar, or practically similar, to the construction illustrated for the upper edge of the door in Figures 2 and 4. With such doors, the main portion or main plane 55 of the door is close to the side wall of the car and the upper edge of the door proper is relatively thin. This permits the use of relatively narrow guide ways between the depending flanges of the track structures and 60 the adjacent portions of the car wall structure and brings the main plane of the door within the guiding or retaining flanges of the track structure. It will also be observed that the supporting rollers, above the top edges 65 of the door, are in planes which are outside

of the main plane of the door so that the points of actual support for the door are outwardly of the main plane of the door and outwardly of a plane passing through the center of weight of the door. This fact, taken in 70 connection with the special formation of the roller brackets or hangers which are carried to points inwardly of the actual points of support, creates a tendency in the door to swing outwardly from or away from the side 75 wall of the car. In other words, due to the particular mounting and particular style of door illustrated, there is a definite tendency for the door to shift or position itself away from and out of contact with the side wall 80 structure of the car, which not only reduces the friction or binding action between the door and the side wall during movement of the door, but is of such nature that compensation is provided in the event the side wall of the 85 car becomes bulged and the door will still be permitted free movement back and forth. As will be understood by those skilled in the art, lower guide brackets are employed for the lower edge of the door, to limit the outward movement of the bottom of the door, such brackets, however, not being deemed necessary of illustration in this application. 90

While I have herein shown and described what I now consider the preferred manner of carrying out my invention, the same is merely illustrative and I contemplate all changes and modifications that come within the scope of the claims appended hereto.

I claim:

1. A fabricated car door hanger made up of pressed sections, and including a body member having a pressed housing portion provided with a side wall and a flange disposed at an angle to said wall, and a complementary pressed portion having a side wall and an integral flange disposed at an angle thereto, said flange being arranged to fit within the flange on said first portion and being rigidly secured thereto, each of the side walls being provided with a journal bearing, and means for providing clearance for a roller adapted to be disposed in said housing, said means including an inwardly pressed portion in the side wall of said housing in proximity to the journal bearing.

2. In combination, a car side having a door opening with a lintel; a door supporting track structure including a horizontal track section, a vertical section against the lintel, and a longitudinally continuous horizontal section extending over the top of the lintel; a guide flange depending from the under side of said horizontal track section; a metal door having its upper edge disposed behind said guide flange; and means for supporting the door including a bracket secured to the door and extending to a point above said track section and provided with a roller riding on said track section.

3. In combination, a horizontally extending track section secured to a car side wall; a guide flange extending downwardly from the under side of said track section and disposed an appreciable distance inwardly from the outer edge of said track section; a door having the upper edge thereof disposed behind said guide flange; and a hanger bracket having a roller engaging said track section 10 along a line disposed outwardly of the plane of said guide flange.

4. In combination, a horizontally disposed track section attached to the outer side of a car side wall; an angle bar secured to the under side of said track section and having one of its flanges depending vertically to form a guide flange disposed inwardly of the outer edge of the track section; a sheet metal door having the upper edge thereof in line with 20 the plane of the main portion of the door and disposed inwardly of said guide flange; and door supporting brackets cooperable with said track section, each bracket having an integral, horizontally extending shoulder disposed directly beneath and normally slightly spaced from the lower edge of said angle bar guide flange to limit the tilting of the door with respect to the track section, the bracket being secured to the door substantially in the main plane thereof.

5. As an article of manufacture, a door hanger comprising: a main section having a securing flange at one end and a flanged, approximately semi-circular roller housing 35 at its other end; and a complemental, flanged, approximately semi-circular roller housing, the flange of said semi-housings being telescoped and the flanges rigidly secured together by means passing through the telescoped flanges.

In witness that I claim the foregoing I have hereunto subscribed my name this 31st day of August 1925.

HAROLD H. HENRICKS.
